DESIGN FOR A CAKE OF SOAP OR SIMILAR ARTICLE

Joseph S. Stein, Chicago, Ill., assignor to Lucien Lelong Inc., Chicago, Ill., a corporation of Illinois

Application May 2, 1936, Serial No. 62,431

Term of patent 3½ years

To all whom it may concern:

Be it known that I, Joseph S. Stein, a citizen of the United States and a resident of the city of Chicago, county of Cook, and State of Illinois,
have invented a new, original, and ornamental Design for a Cake of Soap or Similar Article, of which the following is a specification, reference being had to the accompanying drawing forming a part thereof.

On the drawing:

Figure 1 is a plan view of the top side of the cake of soap showing my new design.

Figure 2 is a plan view of the bottom side thereof, and

Figures 3, 4, 5 and 6 are side or end views thereof.

I claim:

The ornamental design for a cake of soap or similar article, as shown.

JOSEPH S. STEIN.
